UNITED STATES PATENT OFFICE.

DAVID NICKEL, OF MORRIS, ILLINOIS.

DESIGN FOR A CASING FOR DOOR-HANGER FRAMES.

SPECIFICATION forming part of Design No. 27,298, dated July 6, 1897.

Application filed May 19, 1897. Serial No. 637,294. Term of patent 7 years.

To all whom it may concern:

Be it known that I, DAVID NICKEL, a citizen of the United States of America, residing at Morris, in the county of Grundy and State 5 of Illinois, have invented and produced a new and original Design for an Outer Casing for Door-Hanger Frames, of which the following is a specification.

My invention relates to a certain new and 10 original design for an outer casing for barn-door hangers. Said design is illustrated in the drawings by means of three figures, of which—

Looking at the figures, the shape or configuration of the design will be seen to be as follows: The casing is of substantially uniform thickness and has around the outer edge, a short distance therefrom and parallel therewith, an outwardly-convex corrugation A, composed of a circular portion a near the bottom and two tangential portions a' a², extending upward therefrom and joining with the 25 circle by means of a reverse curve. In the angle between the circular portion of the corrugation and the two tangential portions are two converging corrugations a³ a⁴, uniting at the top, as seen at a⁵. 30

The essential features of my design I consider to be the circular corrugation a, joined to the marginal corrugation a' a² by means of reverse curves substantially tangential to the circular portion.

I claim as new and desire to secure by Letters Patent—

The design for an outer casing for door-hanger frames, herein shown and described.

In witness whereof I have hereunto set my 40 hand, at Morris, in the county of Grundy and State of Illinois, this 13th day of May, A. D. 1897.

DAVID NICKEL.
